[57] CLAIM

The ornamental design for a handle tip, as shown and described.

DESCRIPTION

FIG. 1 is a bottom front perspective view of a handle tip showing my new design;

FIG. 2 is a front elevational view thereof;

FIG. 3 is a bottom plan view thereof;

FIG. 4 is a right side elevational view thereof;

FIG. 5 is a left side elevational view thereof;

FIG. 6 is a top plan view thereof;

FIG. 7 is a rear elevational view thereof; and,

FIG. 8 is a top front perspective view, in reduced scale, showing my new design as it would be used with a broom and broom handle. The broken line drawings of a broom and broom handle are for illustrative purposes only and form no part of the claimed design.

The interior of the handle tip that would be visible in FIG. 6 forms no part of the claimed design;
